TOY ANIMAL FIGURE

James Edwin McConnell, Northridge, and Frank Ferrin, Chatsworth, Calif.; said Ferrin assignor to said McConnell

Application June 21, 1948, Serial No. 147,106

Term of patent 14 years

(Cl. D34—2)

To all whom it may concern:

Be it known that we, James Edwin McConnell and Frank Ferrin, both citizens of the United States of America, residing at Northridge, California, and Chatsworth, California, respectively, have invented a new, original, and ornamental Design for a Toy Animal Figure, of which the following is a specification, reference being had to the accompanying drawing, forming part thereof.

Figure 1 is a front elevation of a toy animal figure embodying our new design;

Figure 2 is a side elevational view thereof; and Figure 3 is a rear elevational view of the same.

We claim:

The ornamental design for a toy animal figure, as shown.

JAMES EDWIN McCONNELL.
FRANK FERRIN.
